UNITED STATES PATENT OFFICE.

JOHN NAGEL, OF SPRINGFIELD, OHIO.

CULTIVATOR.

SPECIFICATION forming part of Letters Patent No. 752,852, dated February 28, 1904.

Application filed August 7, 1903. Serial No. 168,685. (No model.)

To all whom it may concern:

Be it known that I, JOHN NAGEL, a citizen of the United States, residing at Springfield, in the county of Clark and State of Ohio, have 5 invented certain new and useful Improvements in Cultivators, of which the following is a specification.

My invention relates to improvements in cultivators, more particularly adapted to two-horse cultivators having two independent series of shovels.

The improvement consists in the constructions shown and described hereinafter, whereby I have a machine easily adjustable for varying conditions of use and adapted to give the best results on account of the adjustable features contained therein. The adjustable features are in the seat of the driver, such that the adjustment can be made for an operator heavy or light in weight.

Another feature is in the adjustment of the shovels to different positions and the automatic adjustment of the carrying-wheels there-with.

Another feature is the adjustment of the height of the seat for the operator and in the peculiar arrangement of the parts.

In the accompanying drawings, Figure 1 is a plan view of my machine. Fig. 2 is a side elevation. Fig. 3 is a detail view of the adjusting device for the shovels connected with the hand-operated lever. Fig. 4 is a detail view of the connections with the foot-lever. Fig. 5 is detail view of the adjusting devices for the seat. Fig. 6 is a detail view of adjusting devices for the carrying-wheels. Fig. 7 is a detail of the connecting devices between the frame of the machine and the shovel.

Like parts are represented by similar letters of reference in the several views.

A and B indicate the frame of the machine, to which the tongue of the machine is connected.

C C represent the carrying-wheels, which are supported by the frame of the machine in the manner hereinafter explained.

To the frame of the machine there is attached by a clip a' a downwardly-projecting U-shaped piece a^2 . (Best shown in Fig. 7.) This piece is pivotally supported within the

clip a' , which is fastened to the frame by nuts. There is journaled loosely upon the said piece a^2 a sleeve a^3 , formed of two parts bolted together, which is integrally formed with a bracket a^4 . This sleeve has oblong openings 55 formed therein, (marked a^5 ,) Fig. 7, and within these openings there fits a connecting-bolt a^6 , which is fastened to the U-shaped piece a^2 at the point a^7 . The purpose is to adjust for the width of cultivators.

The bracket a^4 is formed with openings a^8 , and within this bracket is adapted to be connected the drag-bar of the shovels, it being understood that there is one of these supporting-brackets on each side of the frame, as 65 shown in the drawings. This drag-bar is indicated by a^9 , Fig. 2, and is formed at its head with a bracket-shaped piece a^{10} , which fits over the piece a^8 and is pivotally connected to said piece by bolts a^{11} . I have shown in 70 this manner a connection for the drag-bar of the shovels or drags such that there is some vertical movement of the drag-bars due to the oblong shape of openings a^8 and also some lateral movement of same through pivot-bolts 75 a^{12} , as well as permitting a sliding adjustment of the sleeve a^3 for variation in cultivators.

The U-shaped piece a^2 is formed integrally with a downwardly-projecting plate a^{12} , formed with openings a^{13} , and within one of these 80 openings there is adapted to be fitted a rod a^{14} , which is curved at its end, as shown in Figs. 2 and 7. The other openings are for the swingtrees of the machine. This rod a^{14} extends toward the rear of the machine, 85 and the rear end of same fits within a loop a^{15} on a flat bar a^{16} , Fig. 2, which is connected to the frame of the machine.

There is a U-shaped piece a^2 for each series of shovels, and in the machine shown here I have 90 illustrated the usual construction employing two series of shovels. Each U-shaped piece is formed in the same manner and the connections with each are the same as those just explained. The bar a^{16} is at its rear end, Figs. 1 and 6, connected to a sleeve (marked b) by a clip. There is a bar and a sleeve for each carrying-wheel. This sleeve is supported by a plate b' and is journaled loosely on a shaft b^2 . The shaft b^2 is curved at its downward 100

end and is formed with a spindle b^3 , which constitutes the axle of the driving-wheel. The plate b' rests upon the top side of the spindle, and there is formed within the lower 5 part of the sleeve b a ball-race b^4 , and balls b^5 are adapted to fit within said ball-race to form a ball-bearing between the plate b' and the sleeve. There is a similar connection between the sleeve and shaft at the top. The upper 10 end of the shaft b^2 is formed with a square projecting piece b^6 , and on this piece is fitted one end of the frame for the carrying-wheels, (marked b^7 , Fig. 1.) There is an oblong opening formed in the end of the frame b^7 , and 15 the shaft is pivoted within the opening to said frame.

On each side of the machine-frame there is supported a lever-arm b^8 at the front end of which there is formed a plate b^9 with a series 20 of openings b^{10} , Fig. 3. A pin b^{11} projects upwardly from the carrying-wheel frame b^7 , and this pin is adapted to fit within the openings b^{10} , so that when the arm b^8 is raised the adjustment can be made from one opening to another. The lever-arm b^8 is pivoted at b^{12} to a bar b^{13} , shaped as a double crank, so that the front end of the lever-arm b^8 can be raised by depressing the rear end of same. The rear end of said lever-arm is connected with a lever 25 b^{14} , which is adapted to be depressed by the operator seated on the seat of the machine. A spring b^{15} normally holds the rear end of said lever-arm b^8 in its extreme upper position, and thereby holds the front end of same 30 in engagement with the pin b^{11} ; but when the lever b^{14} is depressed the rear end of said lever-arm will also be depressed against the tension of the spring b^{15} and the front end of the lever-arm be raised so that lateral adjustment 35 of said arm can be made. Whenever said arm is moved laterally, the pivotal connection b^{12} is such that the bar b^{13} is rotated thereby, and the lower end b^{24} of said arm is moved laterally for the purpose hereinafter explained. 40 The lower end of the rod or shaft b^{13} fits within an opening formed by the bracket b^{16} , which is part of the drag-bar for the shovels. Consequently whenever the lower end b^{24} of the bar b^{13} is moved laterally the shovels will be 45 moved a corresponding distance. At the same time the carrying-wheel will also be moved simultaneously by reason of the connection between the frame b^7 and the axle of the wheel. 50

As shown in Fig. 1, I have two series of shovels and a corresponding lever-arm b^{14} , with 55 its connecting parts, for each series, so that the operator by operating both levers simultaneously will effect a quick and accurate adjustment of the parts for cultivating. I have also shown a connection with said shovel frame b^7 , so that the operator can adjust same by moving the foot.

In Fig. 4 I have shown a lever b^{16} , which is 60 fulcrumed on a support b^{17} , which projects from the frame-piece b^{18} , which is supported

by the frame B. At the upper end of this lever b^{16} there is a pivotal connection with a crank-arm b^{19} . The lower end of said lever b^{16} is formed of a shape for easy manipulation by the foot. The crank-arm b^{19} is pivoted on top 70 of the side pieces of the frame B, the tongue-piece fitting within a mortise formed in the frame-piece b^{18} . The clip shown in Fig. 4 binds the tongue to the frame-piece and also forms the pivot for the crank-arm b^{19} . The crank-arm 75 at one end is pivotally connected with the upper end of the lever b^{16} . At the other end the crank-arm b^{19} is pivotally connected with the shovel-frame b^7 . Consequently whenever the foot of the operator causes the lower end of 80 the lever b^{16} to move inwardly or outwardly the crank-arm b^{19} is correspondingly moved, which causes a lateral movement of the frame b^7 . By this construction the operator may by 85 depressing the rear end of the arm b^{14} raise the front end of the lever-arm b^8 and adjust the lever-arm so that with the foot he may operate the lever b^{14} , and thereby cause a greater or less lateral adjustment of the series of shovels, depending on the opening within which is fitted 90 the pin b^{11} . The bar a^{16} is formed at the front end with a series of openings, so that when it is desirable to change the position of the axis of the carrying-wheels the operator can loosen the nut b^{21} and move the bar a^{16} forwardly or 95 rearwardly. When this is done, the lower end of the sleeve b is moved out of vertical line. The upper end of the sleeve is formed with a projecting piece b^{22} , having a convex 100 face formed thereon (marked b^{23}) which permits an adjustment of the upper end of the sleeve by reason of the convex face b^{23} being formed so as to slide over the face of the bar. The sleeves and projecting pieces constitute a supplemental frame for the carrying-wheels. 105 When adjustment is to be made, the bar a^{16} is moved forwardly or backwardly, which throws rear end of sleeve b backward, which throws the fulcrum-point for the machine-frame rearwardly and changes the balance to provide for change in weight of operator. In this manner the sleeve and shaft are adjusted and same are held in the adjusted position by tightening the bolt b^8 . The opening through the piece b^{22} is oval shaped, and the surface 110 against which the head of the bolt abuts is curved, Fig. 6, so as to make a secure adjustment. The seat c for the operator is supported by a brace c' . (Shown in Fig. 5.) This brace has a series of openings at its upper end, and the front end of the seat-bar c^2 is connected with a stepped piece c^3 , which engages with the frame-piece b^{18} . By releasing the bolt c^4 the seat-bar c^2 and the seat c can be lowered or raised, and the stepped piece c^3 can 115 then be adjusted to engage with its notch the frame-bar b^{18} , so as to hold the seat-bar securely in its adjusted position. (See Fig. 5.)

The sleeve a^3 can be moved laterally on the U-shaped piece a^2 and when adjusted to proper 120

position the connecting-bolt a^6 can be adjusted to engage one of the openings a^5 , so as to hold the sleeve in its adjusted position.

The series of shovels are connected by a chain d with a lever d' , which is used in connection with the segment d^2 , so that the shovels can be raised or lowered and held in their adjusted position. In order to avoid interference between the lever and chain, I have shown the lever of a bracket shape, Fig. 2, which insures easy and quick adjustment of the shovels.

In operation it will be understood that the driver seated upon the seat c can quickly shift the drags or shovels for preventing the plowing up of hills of corn. For instance, if there are hills of corn out of line which the machine would otherwise plow up the operator can by depressing the lever b^{14} immediately disconnect the shovel-frame from the carrying-wheel frames and by a lateral movement of the lever b^{14} can throw the shovels to the right or to the left, so as to prevent any injury to the hills of corn. If, however, the operator desires to change the direction of the entire machine, he lifts the lever b^{14} in its raised position, so that when he throws the lever b^{14} to the right or left he moves the carrying-wheels simultaneously with the shovels and in this manner changes the direction of the wheels.

Having thus described my invention, I claim—

1. In a cultivator, the combination of the carrying-wheels, the carrying-wheel frame, shovels, and a shovel-frame pivotally connected to said carrying-wheel frame, a lever normally holding the carrying-wheel frame and shovel-frame connected, and means connected with said lever for causing the two frames to move in unison whenever said lever is moved laterally, but adapted to permit said lever to move vertically and thereby disconnect the two frames, for the purpose specified.

2. In a cultivator, the combination of the carrying-wheels, the carrying-wheel frame, shovels, and a shovel-frame pivotally connected to said carrying-wheel frame, a lever normally holding said frames connected and adapted to cause same to move in unison whenever said lever is moved laterally, separable connecting devices between said lever and said carrying-wheel frame, and means for disengaging said lever from said separable connections by the vertical movement of said

lever while holding connected said lever and 55 the shovel-frame, for the purpose specified.

3. In a cultivator, the combination of the carrying-wheels and the carrying-wheel frame, a series of shovels and shovel-frames pivotally connected to said carrying-wheel frame, a series of levers normally connected to said carrying-wheel frame and the shovel-frame and adapted to be moved laterally, means for moving all said frames by the lateral movement of any one of the levers, and 60 means operated by the vertical movement of said lever for disconnecting any one of said shovel-frames from the carrying-wheel frame, for the purpose of operating any one of said shovel-frames independent of the carrying-wheel frame.

4. In a cultivator, the combination of a carrying-wheel frame, a shovel-frame, a lever pivotally connected to said shovel-frame and adapted when operated laterally to throw said 75 shovel-frame to the right or left, an arm on said lever separably connected to the carrying-wheel frame at one end thereof, and means connected with said lever for operating simultaneously the shovel-frame but adapted to cause 80 the disconnection of said frames whenever said lever is moved vertically and carrying-wheel frame, for the purpose specified.

5. In a cultivator, a machine-frame, a carrying-wheel frame, a rod extending from the 85 front of the machine-frame to the supplemental carrying-wheel frame and connected therewith, a sleeve journaled loosely on said carrying-wheel frame, a convex face formed on its upper end, and means for changing the relative position of said convex face and the machine-frame, for the purpose specified.

6. In a cultivator, the combination of a machine-frame, a carrying-wheel frame, and a supplemental frame for said wheel-frame, a 95 rod extending from the front of the machine-frame to the lower end of the supplemental carrying-wheel frame, a convex face formed on the supplemental frame and engaging the machine-frame, and means for adjusting the position of said convex face in its relation to the machine-frame, for the purpose specified.

In testimony whereof I have hereunto set my hand this 28th day of July, A. D. 1903.

JOHN NAGEL.
